Jacob Felbel

UNITED STATES PATENT OFFICE.

FRANK L. CROSS, OF NEW YORK, N. Y.

CORSET-FASTENING.

SPECIFICATION forming part of Letters Patent No. 412,020, dated October 1, 1889.

Application filed May 23, 1889. Serial No. 311,821. (No model.)

To all whom it may concern:

Be it known that I, FRANK L. CROSS, a citizen of the United States, and a resident of New York city, in the county of New York and State of New York, have invented certain new and useful Improvements in Corset-Fastenings, of which the following is a specification.

My invention has for its main objects to provide a construction of corset clasp or fastening whereby the corset may be conveniently and readily secured upon the wearer, and whereby the corset may be quickly detached or unfastened, and has for its secondary objects simplicity and cheapness of construction.

To these ends my invention consists in certain features of construction and combinations of devices, all of which will be hereinafter more fully described, and particularly pointed out in the appended claims.

In the accompanying drawings, Figure 1 is a plan view of the two parts of a corset-clasp separated, embodying my invention. Fig. 2 is a plan view of the opposite side of one of such parts—namely, that part shown at the left-hand side of Fig. 1, with the studs or posts drawn in section. Fig. 3 is a vertical cross-section taken at the line $x-x$ of Fig. 2, with the companion part shown at the right-hand side of Fig. 1 added in operative engagement. Fig. 4 is a plan view of a modification of the part shown at Fig. 2, with the studs in section. Fig. 5 is a vertical cross-section taken at the line $y-y$ of the last-mentioned figure, with the companion part added.

In the several views the same part will be found designated by the same numeral of reference.

2 designates a busk or one part of the corset-clasp, and 3 the other. These parts may be attached to the body of the corset in any suitable manner, as will be readily understood by those skilled in the art. The busk or part 2 consists of a flexible plate or strip 4, formed or provided along one edge with a series of hooks or jaws 5 and intermediate spaces or openings 6. The hooks or jaws 5 are fixed or permanent, and are so arranged along the busk 2 that their throats or openings extend lengthwise of the same. The

busk or part 3 consists of a flexible plate or strip 7, provided with a series of hooks or headed studs or posts 8 projecting at right angles to the face or side of the busk and 55 adapted to engage with the hooks or jaws 5 on the part 2.

Referring now more particularly to Figs. 1, 2, and 3, it will be observed that the elongated hooks 5, which occupy a position near 60 the center of the plate 4 lengthwise, are formed with transverse saw cuts or slits 9. These are provided to enable the strip or plate 4 to bend to conform to the shape of the wearer and to yield to the body of the person 65 in sitting, stooping, or assuming other postures.

In practice the hooks 5 are arranged on the inside or toward the body of the wearer, as represented at Fig. 1, and provision must be 70 made (to insure comfort to the wearer) for permitting the upper and lower ends of the part 2 to bend easily outward toward each other and to assume the form of a curve or bow.

With the long hooks 5 shown but a slight degree of flexure could be obtained without the presence of the saw cuts or slits, which operate to give approximately the same flexibility to the strip 4 as if the hooks 5 were entirely omitted.

As in practice nearly all the bending or curving occurs intermediate the ends of the part 2, it is not required to provide the slits in those hooks which are located near the extremities of the strip; but, if desired, they may of course be formed therein.

10 designates a spring-plate, which is secured to the plate 4 near one edge and extends laterally to near the points of the hooks 90 5, and preferably in a plane nearly coincident therewith. The spring-plate is connected to the plate 4, preferably, by rivets 11, and between the two plates at each rivet, excepting the middle one 11^a, is placed a small 95 washer 12, through which the shank of the rivet passes, for maintaining the plates at the proper distance apart, or for insuring the elevation of the free edge of the spring-plate, in order that it may co-operate with the hooks 5 100 and the studs or posts 8. Instead of the collars or washers 12, the rivets may be provided

with shoulders, or the spring-plate may be so bent as to dispense with either; but I prefer to employ some intermediate means for the purpose described. The spring-plate is also 5 made of a flexible and elastic substance or material—as steel, for instance.

If the spring-plate were secured immovably to the plate 4, both plates would buckle or crinkle between the rivets; when it should be 10 attempted to bend them, and hence the parts would not only be stiff and uncomfortable to the wearer, but would soon lose their shape and become worthless. In order to avoid this, I construct the parts so that they may slide 15 or move longitudinally independently on each side of the middle portion or rivet. The center rivet 11^a of the two plates may be unprovided with any collar, and the parts 2 4 secured firmly together and in contact at this 20 locality. At each rivet above that marked 11^a the spring-plate is provided with a slot 13, longer than the diameter of the rivet and extending upwardly, and at each rivet below that marked 11^a the spring-plate is formed 25 with a slot 14 of greater length than the diameter of the rivet and extending in a downward direction. The rivets 11 pass through round holes in the plate 4 and through the slots 13 and 14 in the spring-plate, and are 30 headed, as illustrated. By this construction the connected plates 2 4 may be bent as one into loop form or until the ends or extremities of the plate 4 touch each other without buckling or crinkling either part. Thus the 35 device is adapted to readily conform to the shape of the wearer and respond with facility to the movements of the person.

In the use of the clasp or fastening shown at Figs. 1, 2, and 3 it is simply necessary (when 40 it is desired to fasten the corset on the wearer) to overlap the part 3 by the part 2 and press or squeeze the two together to cause the studs or posts 8 to flatten or bend the spring-plate to an extent sufficient to allow the heads of 45 the studs or posts to enter the hooks 5 and engage therewith. As soon as each stud is engaged with its hook the shank of the stud occupies the slot or space 15 between the free edge of the spring-plate and the point of the 50 hook, and the spring-plate resumes its normal position, and thereby effects a locking or positive engagement between the hook and the stud, all as clearly represented at Figs. 2 and 3. When it is desired to remove the corset, 55 it is only necessary to slide or move one or both of the parts 2 3 longitudinally until the posts or studs register or coincide with the spaces or openings 6, when by the pressure of the body the posts will be caused to pass out 60 through said openings, and thus effect a separation of the parts.

In practice I make the distance between the openings or outlets 6 and that between the studs equal, so that when the parts are moved 65 endwise to take off the corset all of the studs arrive at their respective outlets simultaneously, and the corset becomes unfastened at

all points at the same time, as indicated at Fig. 1.

Referring now to Figs. 4 and 5 of the drawings, it will be observed that the hooks 5 are made shorter and the openings or outlets 6 longer than in the other figures, but the principle of operation is the same in both constructions. In lieu of the long continuous 75 spring 10 (shown at Fig. 2) it will be further observed that a series of short independent springs are employed, and these springs, instead of being made separate from and applied to the plate 4, are made integral therewith by 80 cutting out the material on three sides and bending it up to form tongues, as clearly represented in the drawings. The part 3 is adapted to co-operate with the part 2 shown at Figs. 4 and 5 in substantially the manner 85 it does with the part 2 shown at Fig. 2.

The construction shown at Figs. 1, 2, and 3 is preferred for the reason that the corset may be put on and fastened more expeditiously, on account of the presence of the long 90 hooks. With short hooks care must be taken to bring the studs or posts into alignment with the hooks, while with long hooks little or no attention is required in this respect.

In each case it will be seen that the heads 95 of the studs or posts are eccentric or extend laterally in one direction only, or are made L-shaped in cross-section. This is somewhat important, for with full-headed or T-shaped posts it would not be possible to conveniently 100 effect a locking or engagement of the posts and hooks with the springs constructed as shown.

The plate 4 may be perforated or slotted at its outer edge, as seen at 16, for the purpose 105 of enabling the attachment of the corset-body thereto, as represented at Figs. 3 and 5.

Numerous changes in detail construction may be made without departing from the 110 spirit of my invention.

What I claim as new, and desire to secure by Letters Patent, is—

1. In a corset-fastening, the combination, with a busk having a series of studs projecting from its face, of a busk having a series 115 of fixed hooks along its edge, the throats of which are arranged lengthwise of said busk and adapted to receive said studs, and a series of openings between said hooks, adapted to permit the escape of said studs when said 120 busks are moved longitudinally, substantially as set forth.

2. In a corset-fastening, the combination, with a busk having a series of studs projecting from its face, of a busk having a series 125 of fixed hooks along its edge, the throats of which are arranged lengthwise of said busk and adapted to receive said studs, and a spring plate or plates for holding said studs in engagement with said hooks, substantially 130 as set forth.

3. In a corset-fastening, the combination, with a busk having a series of studs, of a busk having a series of fixed hooks the

throats of which are arranged lengthwise of said busk, a spring plate or plates adapted to lock or hold said studs in engagement with said hooks, and a series of openings between said hooks, adapted to permit the intentional escape or disengagement of said studs upon an endwise movement of either of said busks, substantially as set forth.

5 4. In a corset-fastening, the combination, with a studded busk, of a flexible plate or strip provided with a series of hooks, one or more of said hooks being transversely slotted, substantially as set forth.

10 5. In a corset-fastening, the combination, with a studded busk, of a flexible plate having a series of hooks, a series of openings between said hooks, and a continuous spring-plate connected to said flexible plate, substantially as described, to permit of an independent longitudinal movement of the parts at 15 their ends when bent or bowed, substantially as set forth.

15 6. In a corset-fastening, the combination, with a studded busk, of a flexible plate having a series of hooks, a series of openings between said hooks, and a continuous spring-plate provided with elongated holes and a series of securing devices, as rivets, whereby 20 the ends of the two plates are adapted when 25 bent or bowed to move independently, and

thus avoid all buckling or crinkling, substantially as set forth.

7. In a corset-fastening, the combination, with a studded busk, of a flexible plate having a series of hooks, and a spring plate or 35 plates whose free edge or edges extend toward said hooks and form therewith a slot or space, as 15, for the introduction of the studs, substantially as set forth.

8. In a corset-fastening, the combination of 40 a busk provided with eccentric studs, of a busk having a series of hooks, a spring locking-plate, and a series of openings between said hooks, substantially as set forth.

9. In a corset-fastening, the combination of 45 a busk provided with partially-headed studs, and a busk having a series of hooks, and a series of openings between said hooks, the said studs and openings being arranged the same distance apart, so that when the busks 50 are moved endwise the said studs may all simultaneously make their exit from the hooks at the said openings, substantially as set forth.

Signed at New York city, in the county of New York and State of New York, this 21st 55 day of May, A. D. 1889.

FRANK L. CROSS.
